(57) **CLAIM**

The ornamental design for a fuel dispenser, as shown and described.

DESCRIPTION

FIG. 1 is a front view of a fuel dispenser having an open rectangular frame and a screen disposed therein;

FIG. 2 is a back view of the fuel dispenser of FIG. 1;

FIG. 3 is a left side view of the fuel dispenser of FIG. 1;

FIG. 4 is a right side view of the fuel dispenser of FIG. 1;

FIG. 5 is a top view of the fuel dispenser of FIG. 1;

FIG. 6 is a bottom view of the fuel dispenser of FIG. 1;

FIG. 7 is a front perspective view of the fuel dispenser of FIG. 1;

FIG. 8 is a front view of a fuel dispenser showing the second embodiment of our new design;

FIG. 9 is a back view of the fuel dispenser of FIG. 8;

FIG. 10 is a left side view of the fuel dispenser of FIG. 8;

FIG. 11 is a right side view of the fuel dispenser of FIG. 8;

FIG. 12 is a top view of the fuel dispenser of FIG. 8;

FIG. 13 is a bottom view of the fuel dispenser of FIG. 8; and,

FIG. 14 is a front perspective view of the fuel dispenser of FIG. 8.

The broken line shown in all of the drawing figures are for illustrative purposes only and form no part of the claimed design.
